Fig 3

FIG. 1 is a perspective view of a scale for letters or the like showing my new design;

FIG. 2 is a front elevation thereof with the two portions of the scale separated and the weighing numerals exposed; and

FIG. 3 is a top plan view thereof.

The rear of the scale opposite to FIG. 2 is the same in appearance as the front except for the absence of the illustrated numerals and graduations, and the bottom of the scale is plain.

I claim:

The ornamental design for a scale for letters or the like, substantially as shown and described.
